(57) **CLAIM**

The ornamental design for household energy storage battery, as shown and described.

DESCRIPTION

The patent or application file contains at least one drawing executed in color. Copies of this patent or patent application publication with color drawing(s) will be provided by the Office upon request and payment of the necessary fee.

1. Household energy storage battery

1.1 : Reference view 1

1.2 : Reference view 2

1.3 : Front

1.4 : Back

1.5 : Left

1.6 : Right

1.7 : Top

1.8 : Bottom

1. The name of this design product: household energy storage battery. 2. Use of this design product: equipment for saving energy. 3. Design points of this design product: in shape and structure. 4. The picture or photograph that best illustrates the point of the design#reference 1.

1 Claim, 8 Drawing Sheets
